Albert S. Miller
Attorney

UNITED STATES PATENT OFFICE.

ALBERT S. MILLER, OF SLATE, INDIANA.

WIRE-STRETCHER.

SPECIFICATION forming part of Letters Patent No. 359,163, dated March 8, 1887.

Application filed November 25, 1885. Serial No. 183,949. (No model.)

To all whom it may concern:

Be it known that I, ALBERT S. MILLER, a citizen of the United States of America, residing at Slate, in the county of Jennings and State of Indiana, have invented certain new and useful Improvements in Wire-Stretchers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain new and useful improvements in implements for stretching and building wire fences; and it consists in the employment of a clamping device which is adapted to be secured to the post so as to hold 20 the wire while being stretched; and my invention consists in the construction and combination of the parts, as will be hereinafter fully set forth, and specifically pointed out in the claims.

25 In the accompanying drawings, which illustrate my invention, Figure 1 is a side view of a wire fence which illustrates the manner of using my improved wire-clamp. Fig. 2 is a perspective view of the clamps which are 30 adapted to be used upon the fence-posts. Fig. 3 is a perspective view of a combined lever, wire-cutter, and staple-puller which is adapted to be used in connection with my improved wire-clamp.

35 A represents the fence-post of an ordinarily-constructed wire fence, between which the wires are stretched and secured thereto by means of staples.

B refers to my improved reversible clamp, 40 which consists, essentially, of a central connecting-bar, C, which is provided with an offset or raised portion, a, the end of which is curved, as shown at a'. Immediately under this offset a is pivotally attached to the bar C 45 a lever, B', said lever having its end b curved and serrated, while the opposite end is bent outwardly from the bar C and formed into a handle.

The bar C has pivotally attached thereto

bent bars D D, one of the ends of said bars, 50 being enlarged and provided with an opening which is screw-threaded, through which opening passes a thumb-screw, E. The opposite ends of said bars D are bent inwardly toward the thumb-screw, as shown at d, said ends being 55 pointed so that they will enter the sides of the posts. This attachment, it will be observed, can be reversed, so as to be secured on either side of the fence-post, which is accomplished by attaching the parts D D pivotally to the 60 bar C. The lever, which is pivoted to the bar C, can swing to either side of the center, so that it can clamp a wire, the strain upon which may be to either side of the clamp. It will be noticed that the bar C is located near 65 one end of the bent bars D, so that it will be adjacent to the corner or edge of the post, thus allowing the central portion of the post to be exposed, so that the staple can be driven into the post to secure the wire thereon.

70 F refers to a compound lever, which is made up of the parts f f', which are pivotally connected to each other by a bolt, g. The end g' of the member f is bent at right angles, and bifurcated so as to form a claw, which can be 75 advantageously used for withdrawing staples from the posts, and the opposite end of this member is curved, as shown at h. The member f of the lever, at one side of the same, between the bolt g and its end h, is provided 80 with an opening, i, through which a wire may be passed, said wire contacting with the recess i' in the opposite member, so that when the parts of the lever are brought on a line with each other the wire will be cut. The member 85 f' of the lever is bent outwardly or curved at its upper end, and again bent at right angles, so as to form a projecting portion, k, which serves as a stop, which will prevent excessive movement of the parts upon each other. The 90 lower end of the member f' is spread, so as to form laterally-projecting portions k', the terminal portions of which are bent almost at right angles and formed into points, so that they can enter the fence-post. The intermediate portion of the member f' is of increased 95 thickness, so as to form an offset, K, the upper surface of which is curved, as shown at h'.

In constructing a fence with my improved device the clamp B is secured to one of the posts of the fence and another clamp on the post adjacent thereto, said clamps being in a line with each other, and the wire to be tightened is placed between the jaws, as shown. The jaw of the lever is then placed over the wire, said lever being in an almost vertical position, its end bearing upon the post, so that when its upper end is drawn away from the post the wire will be clamped in the jaws and stretched between the posts, and said wire will be held by the jaws of the clamps, and may be secured to the posts by the staples.

15

I claim—

1. The clamp B, consisting of the bent bars D, having thumb-screws, and a connecting-bar, C, pivotally attached to said bent bars

and provided with an offset and pivoted lever, substantially as shown, and for the purpose 20 set forth.

2. The clamps B, consisting of bent bars D, having inwardly-turned ends d and thumb-screws E, said bent bars being connected to each other by a central bar, C, which is pivotally connected thereto at one side of the centers of the bars D, said connecting-bar having an offset, and a pivoted lever, substantially as 25 shown and described.

In testimony whereof I affix my signature in 30 presence of two witnesses.

ALBERT S. MILLER.

Witnesses:

MARTIN L. ROBINSON,
ERASTUS C. LEWIS.
